UNITED STATES PATENT OFFICE.

SCOTT IRVING DRESSER, OF COATICOOK, QUEBEC, CANADA.

FIRE AND BURGLAR ALARM SYSTEM.

Application filed April 4, 1925. Serial No. 20,790.

To all whom it may concern:

Be it known that I, SCOTT I. DRESSER, a subject of the King of Great Britain, residing at Coaticook, in the Province of Quebec and Dominion of Canada, have invented new and useful Improvements in Fire and Burglar Alarm Systems, of which the following is a specification.

My present invention has reference to a combined fire and burglar alarm system.

My object is to arrange in a dwelling an audible alarm actuated by weighted means connected to a breakable and burnable element trained around the different parts of the dwelling and also to the doors and windows thereof as well as other like elements trained to similar parts in a garage, barn or other out-house adjacent to the dwelling, and whereby the severing of any of the said elements will permit of the weighted means actuating the alarm so that the occupant of the dwelling will know that a fire has occurred or a burglary has been attempted.

In addition to the foregoing broadly stated object, the invention further consists in means for severing the inflammable flexible element that actuates an alarm upon the opening of a window or door, and further details of construction as well as the operative arrangement and combination of parts such as is set forth in the following description and pointed out with particularity in the appended claim.

In the drawings which accompany and form part of this application:—

Figure 1 is a perspective view to illustrate my improved fire and burglar alarm system.

Figure 2 is an enlarged side elevation of the audible alarm and the casing therefor.

Figure 3 is a plan view to illustrate the arrangement of the knife or cord severing means on a swinging door.

Figure 4 is an elevation thereof.

Figure 5 is a sectional view through a window casing showing the arrangement of the cord severing means thereon.

Figure 6 is a sectional view on an enlarged scale and approximately on the line 6—6 of Figure 5.

In Figure 1 of the drawings, I have shown diagrammatically a dwelling 1, a garage or stable 2 and a barn 3. Between the dwelling 1, the garage and the barn there are arranged pipe members 3, and through these pipe members there are trained flexible ele-

ments 4 and 5 respectively. The elements 4 and 5 are of an inflammable nature, and as disclosed in the diagram of the barn in the said Figure 1, the element is trained through suitable guide means 6 around the side and the top or roof of the barn. Also the element received in the barn may be arranged in a manner hereinafter to be described adjacent to the doors of the barn. In the showing of the drawings, the end of the flexible element has its end secured to the top of the barn. The flexible element 5 leading through the pipe 3 to the garage 2 is trained through guide means in the said garage and has its end passed through an opening in a plate 7, the said end being knotted, as at 8. The plate is formed on one end of a bracket 9 that is suitably supported in the garage. Pivoted to one end of the plate there is a lever 10. The lever is provided with an inwardly flared opening 11 through which the flexible element 4 passes. The opening 11 is arranged near the pivot 12 between the lever and the plate 7. The reamed opening provides a cutting edge at the lower face of the lever 10 so that a swinging of the lever will sever the cord 4. The outer end of the lever 10 is connected by a link or similar element 13 to the swinging door 14 of the garage, so that the opening of the garage will sever the flexible element 4. Also a fire occurring in the garage will likewise sever the flexible element.

The cutting means for the inflammable element 4, described only in connection with the garage 2 is also designed for use on other similar flexible and inflammable elements that are trained through parts of the dwelling 1 and the barn 3 or other out-buildings where doors or swinging windows are employed. The dwelling 1 has also arranged therein a flexible inflammable element 15 which has branches connected to brackets similar to the brackets 9 and through flared openings in levers similar to the lever 10, these levers, as previously inferred, being connected by means similar to the means 13 to the swinging doors. In addition to this other branches of the flexible element 15 are trained through cutting eyes in levers 16 which are pivoted adjacent one of their ends on brackets 17 secured to window casings. The levers 16 opposite the pivot ends thereof are provided with elements 18, preferably but not necessarily of

a breakable nature, the said elements being connected to or contacting with small brackets 19 on the window sash. An attempt to open the window sash will result in the swinging of the lever 16 so that the branches 20 of the element 15 will be cut.

All of the flexible elements 4, 5, and 15 have their ends received in the dwelling 1 connected to weights 21 respectively, and 10 these weights are in the path of contact with a flange or platform 22 formed on an offset end of a lever 23. The lever is received in and is pivotally connected to the frame or casing 24 of a spring wound motor 15 25. The main toothed wheel of the motor operates a pinion on whose shaft there is a disk 26. The disk is provided with a notch 27, and the end of the lever arranged thereover is formed with a finger 28 to be 20 received in the notch. The lever is influenced by a spring 29 to bring the finger over the periphery of the disk 26 and into the notch 27. On the referred to shaft for the disk 26 there is an escapement wheel 25 30 engaged by the teeth of an escapement element 31 and the shaft for the element 31 has secured thereon a rod 32 provided with a head 33 which is contractable with an audible alarm in the nature of a bell 34. 30 Thus it will be apparent that upon the breakage of any of the flexible elements the weight 21 connected thereto will drop on to the flange 22 of the lever 23, causing the swinging of the same to bring its finger 35 28 out of the notch of the disk 26 and thereby permit the turning of the motor and impart a vibratory or swinging movement to the head carrying rod 22 to cause the same

to intermittently contact with the bell 34 and sound the alarm. By this simple means 40 the occupant of the dwelling will be continuously notified that a fire in his dwelling, garage, barn or other out-building has occurred or that an attempt has been made to burglarize such buildings. The alarm, 45 of course, will be sounded as long as the motor is operated and the motor is operated as long as the weight 21 remains on the lever.

Having described the invention, I claim:— 50

A combined burglar and fire alarm, comprising a motor operated alarm, and said motor including a notched wheel, a pivotally supported brake lever having a tooth to engage in the notch of the wheel to hold the 55 motor inactive, weights suspended above the lever, flexible burnable and breakable elements to which the weights are attached, and said elements designed to be trained around the rooms of a building, a bracket 60 to which the ends of the elements are secured, a lever pivotally secured on the bracket having a flared opening terminating in a knife edge through which the flexible element passes, and said lever having a 65 loose connection with a swingable or movable portion of the building such as a door or window whereby the lever will be swung upon the opening of such element to sever the flexible element and permit of the weight dropping on to the brake to influence the latter to permit of the actuation of the motor.

In testimony whereof I affix my signature.

SCOTT IRVING DRESSER.
